UNITED STATES PATENT OFFICE.

JEREMIAH C. SINCLAIR, OF TOLEDO, OHIO, ASSIGNOR OF ONE-HALF
TO HOMER HOOD, OF SAME PLACE.

TYPE-WRITING MACHINE.

SPECIFICATION forming part of Letters Patent No. 510,653, dated December 12, 1893.

Application filed August 6, 1892. Serial No. 442,825. (No model.)

To all whom it may concern:

Be it known that I, JEREMIAH C. SINCLAIR, of Toledo, county of Lucas, and State of Ohio, have invented certain new and useful Improvements in Type-Writing Machines; and I do hereby declare that the following is a full, clear, and exact description of the invention, which will enable others skilled in the art to which it appertains to make and use the same, reference being had to the accompanying drawings, and to the figures of reference marked thereon, which form part of this specification.

My invention relates to a typewriting machine, and has for its object to simplify the construction, cheapen the manufacture, and render the operation easier than heretofore by dispensing with the necessity of manually operating certain parts.

The invention consists in the parts and combinations of parts hereinafter described and pointed out in the claims.

In the drawings—Figure 1 is a plan view of a complete typewriter. Fig. 2 is an end elevation with the side plate removed. Fig. 3 is a sectional detail view showing the type bars and the connection of the key levers therewith. Fig. 4 is a front elevation of a portion of the carriage and carriage support. Fig. 5 is a transverse vertical section on lines $x-x$ Fig. 1. Fig. 6 is an end view of the carriage, and carriage support illustrating the means employed for returning the carriage, and also the mechanism for feeding the ribbon. Fig. 7 is a transverse section through the frame of the machine on lines $y-y$ Fig. 1 showing a modified form of mechanism for returning the carriage, this mechanism being located at the end opposite to that shown in Fig. 6.

Fig. 8 is an edge view of the mechanism on the top plate shown in Fig. 7. Fig. 9 is an end view of the mechanism shown in Fig. 7 looking directly at the end of the machine. Fig. 10 is a detail view of the spool shaft and spool, showing the means employed for holding the spool in adjustment. Fig. 11 is a detail view of one of the pawls. Fig. 12 is a plan view of the cleaning brush and operating lever. Fig. 13 is a side view of the same. The frame of the machine comprises base plate 1, top plate 2, rear end plate 3, curved

front plate 4 and front end plate 5. Formed integral with the top plate at each end are two rectangular projections 6, into which are journaled screw-threaded shafts 7 upon which is mounted a carriage support comprising a front bar 8, end bars 9 and a rear rod 10. Journaled in end bars 9 is a screw shaft 11 extending the entire length of the carriage support, and provided at one end with a disk 12 having four projecting pins 13 with which the hook of a bar 14 engages to revolve the same when the bar is pulled downward by a key lever 15 fulcrumed at 15' and normally raised at the outer end to exert a downward pull upon bar 14 by reason of a spring 16 secured at the base of the machine, and pressing against the under side of the lever. The bar 14 is normally held in engagement with pin 13, by means of a spring 14'. See Fig. 2.

It will be seen from the foregoing that when the outer end of lever 15 is depressed, bar 14 is raised, and the hook of the bar will engage a pin 13 when upon releasing the spacing key, the spring will raise the front end of the lever, and cause the rear end to be depressed, thereby revolving the wheel a one-fourth turn which gives to the carriage the proper movement to space the letters, any further spacing being given by merely depressing the spacing key, as many times as necessary to advance the carriage the desired distance. I have provided however, for an automatic control of the lever 15 for spacing between the letters, which consists in extending a bar 17 at right angles to lever 15 and connected with the end, so that when any of the key levers are operated to print a character, it depresses the outer end of the lever 15 and when the key is released the same operation takes place and the screw shaft is given one-fourth turn.

The carriage comprises a rectangular frame of less area than the carriage support, and is composed of a front side bar 18, and a rear side rod 19 and end bars 20. The carriage is suspended within the carriage support by means of two metal blocks 21 secured firmly upon rod 19 and having a screw threaded perforation into which screw shaft 11 is run, so that the revolution of the shaft as has been described, will give longitudinal movement

to the carriage in either direction, according to the direction of rotation of the screw shaft, the opposite or front side of the carriage being provided with traveler wheels 22 which roll upon bar 8 of the carriage support frame. Bar 14 being employed to revolve the screw shaft to advance the carriage when writing, I will now describe the means employed to revolve the screw shaft in an opposite direction to return the carriage.

Referring to Figs. 1, 5, and 6, 23 designates a gear journaled upon the right hand side of the machine within the frame, and meshes with a small pinion 24 secured upon the end 15 of the screw shaft 11, there being a barrel 23' upon the gear, to which a strap 25 is secured, the strap passing below an idler pulley 26 secured in hangers attached to the base of the frame, and secured at the opposite end to the 20 end of a lever 27 fulcrumed upon the frame at 27' and extending beneath the key board, and provided with a key. In this construction the revolution of the screw shaft to advance the carriage revolves pinion 24, gear 25, and barrel 23' and winds strap 25 upon the barrel, so that when it is desired to 25 revolve the shaft to return the carriage, the outer end of lever 27 is depressed, causing a pull upon the strap, and a rapid revolution of 30 the screw-shaft through the multiplying gears 23 and 24.

In Figs. 7, 8, and 9 I have shown a modified form of mechanism for returning the screw shaft, Fig. 9 being a somewhat enlarged view. 35 In this construction gear 23 is movable upon its shaft, but revolves therewith being secured by a key and a key way. Upon the same shaft with gear 23 is secured a ratchet wheel 28 and brake wheel 29, there being a 40 coiled spring 30 secured at one end to a pin 31^a projecting from the frame the opposite end being secured to the ratchet wheel, so that when the ratchet wheel is revolved the spring is put in tension. Ratchet wheel 28 45 and brake wheel 29 are revolved by means of a pawl lever 31, and pawl 32, lever 31 being connected with a lever 33' the outer end of the lever being provided with a cross bar 34 with which the key levers contact to 50 cause the pawl to revolve ratchet wheel 28 one notch or the distance of one ratchet each time a character is printed, or a space formed. In order to hold the ratchet wheel against the 55 tension of the spring, a pawl 35 is pivotally secured upon a bar 36 pivoted upon the frame in a manner to engage with the ratchet wheel and hold the same as advanced from return movement. By this arrangement the spring is put in tension as the screw shaft is advancing the carriage and being in slight tension initially, it is ready to return the carriage upon the release of the pawls 32 and 35 and engagement of gears 23 and 24, whether the carriage has traveled the distance to form 60 but a character of a line, or the entire length. In order to engage the gear 23 with gear 24 and at the same time release pawl 35, I at-

attach a spring 37 to a lug 38 upon the frame and curve the spring centrally perforating it at this point to allow the spring to receive 70 the journal of wheel 23, and attach the spring to the wheel so that the outward normal tension of the spring will hold gear 23 out of mesh with pinion 24, the lower end of the spring being inclined away from the wheel 75 and bent at an acute angle at 39, there being a bar 40 bent at the upper end at an opposite angle to angle 39, so that as the bar is raised by depressing lever 41 to which bar 40 is pivoted, the spring is forced in carrying the gear 80 23 with it and forcing it into mesh with pinion 24. Bar 36 to which pawl 35 is pivoted is formed with an angular arm 42, the end of which is in a path of travel of a pin 43, upon bar 40, and as the bar 40 is raised the pin contacts 85 with arm 42 and trips the pawl (pawl 32 having normally dropped from contact with the ratchet wheel) thereby releasing the ratchet wheels, and allowing the spring to act upon the same causing gear 23 to revolve gear 24, and 90 the screw shaft to return the carriage. Should the spring revolve the gears with too great rapidity, a further depression of lever 41 will apply brake 44 secured to bar 40 by means of an angular hanger 45, and check the speed of 95 rotation of the same. As each type lever is supplied with upper and lower case type and characters, the carriage is moved forward to print the capitals, and this movement is accomplished by revolving screw shafts 7 100 through the medium of quadrant shaped rack bars 46 pivoted to the frame at 46', and meshing with miter gears 47 upon shafts 7, there being levers 48 connected with rack bars 46 and operated by a key marked in the drawings "shift" it being understood that the two 105 levers 48 are connected by a cross bar 48' so that the two levers work in unison to revolve the quadrant rack bars to advance the carriage support toward the operator, the levers 110 being raised to return the carriage by means of a spring 50 secured at one end to the upper portion 3 of the frame and bearing at the free end upon the lever, so that the carriage is advanced by rocking the quadrant rack bar, on depressing the key, and returned by the action of the spring, as it returns the levers to their normal horizontal position, and in the act rocks the quadrant rack bar to reverse the direction of rotation of the screw 115 shafts 7.

51 designates the platen, revolvably journaled upon the carriage, and provided with a wheel 52 at the right hand side of the machine, by which to turn the same manually, 125 the opposite end being formed with a circular ratchet face 53 by which to automatically revolve the platen through the medium of a mutilated gear 54 journaled upon the carriage and meshing with a gear 55, also journaled 130 upon the carriage and provided with a pawl 56 which engages with the ratchet face 53 of the platen.

Gear 54 is formed with a depending tooth

54' having an inclined side adapted to ride over a catch 57 pivoted at the left hand side of the frame and allowed to swing outwardly sufficient to allow the tooth to pass the same but prevented from swinging inwardly by a stop 57' so that as the carriage is returned, tooth 54' will ride over catch 57 and engage the same, and as the carriage moves to the right the gear 54 will be given a partial turn communicating a like motion to gear 55 and pawl 56, which gives to the platen a rotary movement sufficient to space a line, the spring 58 returning gears 54 and 55 to their original position.

15 In order to notify the operator of the near approach to the end of the movement of the carriage, I have provided for a plurality of alarms by means of a catch 59, pivoted to the carriage support and allowed to swing out of 20 the way when the carriage is being returned, but prevented from swinging in an opposite direction by means of a stop 59'.

60 designates a lever fulcrumed centrally and formed with a plurality of notches 60' at 25 one end and a hammer at the opposite end adapted when the lever is depressed at the end upon which the notches are formed by riding over the catch, and allowed to rise by reason of the notches to sound an alarm by 30 reason of the hammer striking a gong 61, the alarm being sounded once for each notch, and again as the lever passes the catch finally, causing three alarms if the carriage is moved to cause the lever to fully pass the catch the 35 free swinging movement of the catch toward the left hand side of the machine allowing the return of the carriage as the catch swings freely when the lever contacts therewith.

62 designates a guide for the paper comprising arms to which is secured a rod 63 by 40 which to align the paper there being a guide 64 upon the rear side of the platen.

I provide for a continuous wind of the ribbon in either direction by means of revoluble 45 shafts upon the outer ends of each of which is secured wheels 65, having four projecting pins, with which the hook ends of bar 66 engage, the bars being hooked upon each side of their upper ends, and secured at their 50 lower ends to a lever 67 operated by the key levers as the opposite end of cross bar 17 attached to lever 15 is secured to the end of this lever by which means a synchronous movement is given to bars 14 and 66, and the 55 ribbon is advanced and revolved from one spool 70 to the spool 70 upon the shaft upon the opposite side of the platen. The bar 66 is held in engagement with the pin of wheel 65 by means of a spring 66' as shown in Fig.

60 5. When the ribbon has been wound from one spool to the other, bars 66 are shifted from one side of the pin-wheels to the opposite side to give a reverse movement to the spools. In order to shift the ribbon laterally 65 to present a new surface to the type the spools are movable upon their shafts as shown in Fig. 10, and are held in adjustment by

means of a spring dog 71 which engages notches formed in the key which key prevents the spool from rotating upon the shaft.

70

72 designates an ordinary friction roller, for insuring a proper movement of the paper.

The type bars comprise each a single rod or wire with a horizontal portion 73, journaled in grooves formed in semi-circular boards 74 having top plates 75 of semi-circular configuration, and formed with co-incident grooves so that the rods are closely confined but prevented from other than rotative movement. The rear ends 76 of the type bars are bent vertically downward from the horizontal portions, and are provided with the type and type characters usually employed in type writing both in small and capital letters, the capitals being arranged above the small letters. The opposite ends 77 of the type bars are bent horizontally at right angles to the horizontal portions and are connected with the key levers, which are right angled levers the horizontal portions 78 of which are fulcrumed upon a rod 79 and 90 the vertical portion 80, connected with the type bar so that by depressing a key 81 the vertical portion 80 of the key lever rocks the horizontal portion of the type bar, and raises the end 76 to cause the same to contact with the ribbon and print the character. In order to regulate the movements of the key levers to cause each character to impact with the ribbon with the desired force, and to prevent an excessive impact, a bar 82 is arranged across 95 the machine above the horizontal portions of the levers and provided with set screws 83, one for each lever, and directly over each lever, whereby the finest adjustment may be made to the movement of each lever.

105

In order to assemble the type bars within the smallest area, and to cause the type to strike at the proper point, in perfect alignment, the horizontal portions 73 are arranged at such an obtuse angle to the impact point 110 of the type as will bring the type to a common point when elevated.

In order to clean the type mechanically, I provide a brush 84 of semi-circular form and secure the same to a swinging frame 85, which normally rests below the type, and arrange a lever 86 which when depressed at one end raises the brush and causes the same to remove any foreign substance from the type that may be thereon. The keys are formed with a horizontal portion with which the fingers contact, and a vertically inclined portion 88 immediately in front of the operator, and designed to receive the character to indicate the particular key to be depressed, this 120 arrangement being of great value as it presents the character in proper position to be more readily observed, than when placed upon the top of the key.

115

In operation, the carriage being at the extreme movement to the left of the machine, and the paper properly arranged upon the platen, the operator depresses the keys in the act of writing, which depresses the outer ends

125

130

of levers 15 and 67, revolving the screw shaft 11 by lever 15 and the action of bar 14 upon wheel 12, and revolving the ribbon spools by the action of lever 67 and bars 66, until the carriage has advanced to its limit, the alarm being sounded in the meantime by lever 60 contacting with catch 59, when the carriage is returned either by depressing lever 27 and pulling upon strap 25, or by depressing lever 41 and releasing the pawl to allow spring 30 to act. When carriage has returned the full limit of its return movement tooth 54' is in engagement with catch 57 when upon the forward movement of the carriage the gears 54 and 55 are given a sufficient turn to cause pawl 56 to turn the platen the distance to space a line.

If it is desired to use capitals, levers 48 are depressed causing the quadrant rack bar to 20 revolve shaft 7 and advance the carriage support and carriage.

What I claim is—

1. In a type writing machine, the combination with a support, of a threaded shaft journaled therein at the rear, the carriage connected with the shaft at its rear side, a disk upon one end of the shaft having laterally projecting pins, a hooked rod for engaging the pins, the lever attached to said rod and 30 the key levers for operating the same.

2. In a type writing machine, the combination with a carriage and its support, of the transverse screw shafts upon which said support is mounted, the shifting lever and devices connected therewith for revolving said screw shafts simultaneously to shift the carriage.

3. In a typewriting machine, a carriage support, a carriage supported thereon, a screw 40 shaft journaled in the carriage frame, a screw threaded connection from the carriage to the screw shaft, a pinion upon the screw shaft a gear meshing therewith, a lever, flexible connections between the gear and lever, means 45 for revolving the screw shaft to advance the carriage and wind the strap, and a key for depressing the lever to unwind the strap and return the carriage.

4. In a type writing machine, a carriage support, a carriage supported thereon, means for moving the carriage longitudinally, and means for imparting a front and back movement to the carriage support, by means of screw shafts journaled in the frame and passing through 50 threaded supports of the carriage support, gears upon the ends of the shafts and rack bars meshing with the pinions, and a key for

actuating the rack bars to revolve the screw shafts.

5. In a type writing machine, a frame, screw 60 shafts journaled upon each side, a carriage support mounted upon the screw shafts by threaded supports through which the screw shaft passes, a screw shaft journaled in the carriage support a carriage mounted upon 65 the screw shaft by threaded supports through which the screw shaft passes, and means for revolving the last named screw to impart longitudinal motion to the carriage, and means for revolving the end screws to impart lateral 70 motion to the carriage.

6. In a type writing machine, a carriage support, a carriage mounted thereon, a platen journaled in the carriage, and provided with a circular ratchet upon one end, a catch upon 75 the machine pivoted to swing freely in one direction but rigid with relation to an opposite movement, gears upon the carriage one of which engages with the catch as the carriage is advanced from the limit of its return 80 movement, a pawl upon an intermeshing gear which contacts with the ratchet teeth upon the platen, whereby the platen is automatically revolved by the advance movement of the carriage.

7. In a type writing machine, an alarm mechanism, comprising a lever pivoted to the carriage support having a plurality of notches at one end and a hammer at the opposite end, a gong secured in the path of travel of the 90 hammer, and a catch pivoted upon the carriage adapted to swing freely in one direction, but secured from movement in an opposite direction.

8. In a type writing machine, a carriage support, shafts journaled upon each side thereof, ribbon spools upon the shafts wheels upon the outer ends of each shaft, projections upon the wheels, a lever fulcrumed upon the machine key levers pivoted upon the machine, 100 and contacting to actuate said lever, bars formed with ends for engaging the projections upon the wheels upon each side, the opposite ends of the bars being secured to the fulcrumed lever, whereby when the type is 105 actuated the ribbon is moved in either direction, as desired.

In testimony that I claim the foregoing as my own I hereby affix my signature in presence of two witnesses.

JEREMIAH C. SINCLAIR.
